UNITED STATES PATENT OFFICE.

DOSSA D. EVINS, OF WACO, TEXAS.

METHOD OF MAKING ELECTROTYPE EMBOSsing-DIES.

1,154,179.

Specification of Letters Patent. Patented Sept. 21, 1915.

Application filed April 24, 1914. Serial No. 834,255.

To all whom it may concern:

Be it known that I, DOSSA D. EVINS, citizen of the United States, residing at Waco, in the county of McLennan and State of Texas, have invented certain new and useful Improvements in Methods of Making Electrotype Embossing-Dies, of which the following is a specification.

My present invention relates to a new and improved method of making electrotype embossing dies for printing and embossing reproductions of any woven fabric such as lace, embroidery and the like.

The primary object of my invention is the construction of dies of the above described character by the use of a sample of the lace, embroidery or other fabric to be imitated. The dies, when properly constructed, will emboss and print a representation of the fabric upon paper or other suitable material in such a manner as to give the finished article the appearance of a sheet of paper upon which the lace or fabric itself is mounted.

The importance of dies capable of performing such work will be readily understood when it is realized that by this means embossed paper samples of various fabrics, particularly laces and embroidery work, may be used by drummers, salesmen, mail order houses and the like in place of actual samples of the fabric for sale.

A further object of my invention is to provide a method of constructing dies of the above described character which will permit their rapid manufacture upon an economical scale.

With these and other objects in view, my invention will be more fully described, illustrated in the accompanying drawing, and then specifically pointed out in the claims which are attached to and form a part of this application.

In the drawings, Figure 1 is a plan view of a sample of embroidery work from which the dies are to be made; Fig. 2 is a perspective view of an electrotyper's wax-case, showing the embroidery sample properly applied thereto; Fig. 3 is a vertical sectional view, showing the manner of making the impression in the wax; Fig. 4 is a corresponding sectional view of the unbacked male die formed by electroplating the wax impression provided as shown in Fig. 3; Fig. 5 is a longitudinal sectional view of the completed dies; Fig. 6 is a perspective view

of a sheet of paper embossed and printed with the dies so formed.

Corresponding and like parts are referred to in the following description and indicated in all the views of the drawing by the same reference characters.

My improved embossing and printing die manufacturing method consists of a number of successive steps, the first of these being the making of a wax impression of the embroidery or other fabric which the dies are to imitate. In accomplishing this, I employ an electrotyper's wax-case 10 of the usual or any preferred type, the case, of course, being filled in the usual manner with electrotyper's wax 11, the surface of which is dusted with graphite or black lead. The fabric sample 12, to be imitated, is then dusted with black lead and placed face down upon the wax, as shown in Fig. 2, after which a sheet of zinc 13, having a smooth lower face, which is also dusted with graphite, is placed over the fabric and pressed down to force the fabric into the wax, this of course causing the wax to pass through the interstices of the fabric until it contacts with the lower face of the zinc sheet or plate.

Although a zinc plate is preferred as the pressure applying means for forming the wax impression, it will of course be understood that any article having a smooth plain surface may be employed with equally good results. The plate is then raised and the fabric removed from the wax, a clear impression of the fabric in all its details having been formed in the wax surface. The graphite coating on the various parts, above described, prevents the fabric sticking to the wax or to the plate and also prevents the plate sticking to the wax. Furthermore, the coating of graphite upon the wax is necessary for the electroplating of the impression so formed, which electroplating constitutes the second step of the process.

The surface of the wax carrying the impression is then electroplated, preferably with copper, in the manner well known to electrotypers, the wax-case serving as the cathode and a copper plate as the anode, the electrolyte being preferably a saturated solution of copper sulfate, acidulated with sulfuric acid. After a shell 14 of the desired thickness has been deposited upon the wax, the shell so formed is removed and backed in the usual manner, as shown at 15, with

type metal or other suitable alloy to give it the requisite strength and stiffness.

The above described is the male die and the female die is formed by dusting the male die with graphite and then electroplating over this graphite in the same manner in which the wax impression was electroplated, the second shell 16 so formed being removed and backed in the same manner in which the 10 first shell is backed, as shown at 17. The female die so formed is the die which carries the ink, if the paper is to be printed as well as embossed.

The dies are employed in the usual manner and it will of course be clear that the 15 paper or other material may be embossed to give merely a raised facsimile of the fabric or that by inking the female die, the paper may be simultaneously embossed and 20 printed. This latter employment of the dies is usually preferred as it provides a background for the representation of the fabric showing the weave and pattern to far greater advantage.

25 The embossed sheet 18, shown in Fig. 6, illustrates the product of the dies formed from the sample shown in Fig. 1 when the female die is inked to print the paper as well as to emboss it.

30 Having thus described the invention, what is claimed as new is:

1. A method of forming an embossing die for embossing material in imitation of a

fabric, which consists in placing the fabric to be imitated upon a properly prepared 35 wax surface, in applying a smooth surfaced body against the fabric, in exerting high pressure against the body to force the wax into and through the interstices of the fabric and against the body, in removing the body 40 and fabric from the wax impression formed, and in then electroplating the impression to produce the die.

2. A process of forming a printing and embossing die for printing and embossing 45 material in imitation of a fabric, which consists in placing the fabric to be imitated face down upon a properly prepared wax surface, in applying a smooth surfaced metallic plate against the outer face of the 50 fabric, in applying high pressure against the plate to force the wax into and through the interstices of the fabric and into engagement with the plate, in removing the plate and fabric, and in then electroplating 55 the impression so formed to produce the die, those portions of the wax engaging the plate forming the portions of the wax impression which, when electroplated, form the printing surface of the die.

In testimony whereof I affix my signature in presence of two witnesses.

DOSSA D. EVINS. [L.S.]
